UNITED STATES PATENT OFFICE.

ROBERT B. DULA, OF ST. LOUIS, MISSOURI.

TOBACCO-RACKING DEVICE.

SPECIFICATION forming part of Letters Patent No. 460,003, dated September 22, 1891.

Application filed January 27, 1891. Serial No. 379,240. (No model.)

To all whom it may concern:

Be it known that I, ROBERT B. DULA, of the city of St. Louis, in the State of Missouri, have invented a certain new and useful Improvement 5 in Tobacco-Racking Devices, of which the following is a full, clear, and exact description, reference being had to the accompanying drawings, forming part of this specification.

My present invention refers to certain improvements in the class of machines shown and described in my application for patent filed August 24, 1889, Serial No. 321,889; and my present invention relates to cutting devices for severing the tobacco that laps from one rack onto another, the invention consisting in features of novelty hereinafter fully described, and pointed out in the claims.

Figure I is a top or plan view illustrative 20 of my invention. Fig. II is an elevation of the gearing for operating the knife or cutter. Fig. III is a vertical section taken on line III-III, Fig. I. Fig. IV is a detail view illustrating the manner of connecting the cutting blocks or strips to the carrying-belts.

Referring to the drawings, 1 represents racks upon which tobacco is spread, as in my application referred to, by a suitable mechanism—as, for instance, such a mechanism as 30 that shown and described in my application for patent filed August 24, 1889, Serial No. 321,888. A mechanical device of this or any other kind for spreading the tobacco upon the racks laps the tobacco from one rack onto another, so that it becomes necessary to sever the tobacco between the racks, and it is to a mechanism for doing this that my present invention relates. The racks 1 are carried upon endless belts 2, passing around supporting and 40 operating drums 3, only one of which is shown, as to this my present invention does not re-

late. Secured to the belts, as shown in Fig. IV, at intervals apart equal to the width of the racks are blocks or strips 4, between which the racks are placed upon the belts. On the 45 upper surface of these blocks rubber or other elastic strips 5 are placed, so as to form a good cutting-surface for the knife.

6 represents a rotary knife secured to a shaft 7, journaled in boxes 8, secured to the 50 frame 9. The knife is operated by a belt-and-pinion connection 10 with the drum 3, (see Fig. II,) and the operating mechanism is so disposed that each time one of the cutting-blocks 4 comes over the drum 3 the knife will 55 come down upon the block, as shown in Fig. III, and sever the tobacco lapsing from one rack onto another.

Under my invention a very cheap and effective device is produced. 60

I claim as my invention—

1. In a device for racking tobacco, the combination of the racks, carrying-belts, cutting-blocks secured to the belts, and a knife, substantially as and for the purpose set forth. 65

2. In a device for racking tobacco, the combination of the racks, carrying-belts, cutting-blocks secured to the belts, and a rotary knife, substantially as and for the purpose set forth. 70

3. In a device for racking tobacco, the combination of the racks, carrying-belts, a drum over which the carrying-belts pass, cutting-blocks secured to the belts, a rotary knife, and a connection between said drum and the shaft of the knife, whereby the knife is caused to 75 operate upon the said cutting-blocks as they pass over said drum, as specified.

ROBERT B. DULA.

In presence of—

THOMAS KNIGHT,
E. S. KNIGHT.
